United States Patent Office

Des. 192,244
Patented Feb. 20, 1962

192,244

END STANDARD FOR A ROW OF SEATS

Herbert E. Williams, Temple, Tex., assignor to American
Desk Manufacturing Company, Temple, Tex., a cor-
poration of Texas

Filed Jan. 16, 1961, Ser. No. 63,559

Term of patent 14 years

(Cl. D15—8)

FIGURE 1 is a perspective view of an end standard for a row of seats embodying my new design;

FIGURE 2 is a side elevational view thereof;

FIGURE 3 is a front elevational view thereof; and

FIGURE 4 is a vertical sectional view thereof taken on line 4—4 of FIGURE 2.

The dotted lines are for illustrative purposes only.

I claim:

The ornamental design for the end standard for a row of seats, substantially as shown and described.
